UNITED STATES PATENT OFFICE.

JOHN CALHOUN CLARK, OF ATLANTA, GEORGIA.

VAPOR-CONDENSER.

No. 889,201.

Specification of Letters Patent.

Patented June 2, 1908.

Application filed December 21, 1906. Serial No. 348,970.

To all whom it may concern:

Be it known that I, JOHN CALHOUN CLARK, a citizen of the United States, and a resident of Atlanta, Fulton county, State of Georgia, 5 have invented certain new and useful Improvements in Vapor-Condensers, of which the following is a specification.

My invention relates to condensers and especially to such condensers as are adapted 10 for cooling the gases in the manufacture of sulfuric acid, and my invention consists in a condenser having a series of superposed casings and transverse cooling tubes connected with each other and with a water supply as 15 fully set forth hereinafter and as illustrated in the accompanying drawing, in which

Figure 1 is a sectional elevation of a condenser embodying my improvements; Fig. 2, a sectional elevation on the line 2—2 Fig. 20 1; and Fig. 3, a sectional plan on the line 3—3 Fig. 1.

The upright structure A has double walls inclosing a chamber X extending the length 25 of the structure, and the space between the inner wall 1 and the outer wall 2 is divided by horizontal partitions 3 into a series of superposed casings each inclosing a chamber y, which in case of a round structure is annular. Across the chamber X, and through 30 the inner walls 1, extend, preferably horizontally, series of tubes 5 upon different parallel horizontal planes, each series communicating at opposite ends with one of the chambers y, or, where the structure is rectangular and 35 there are separate chambers y at each side, the tubes 5 communicate each with chambers at opposite sides of the structure.

At the lower end of the structure an inlet opening 7 communicates with an inlet duct 40 or pipe 8 and an outlet opening 9 at the top communicates with an outlet pipe 10, and in some cases a spray device C at the top of the chamber communicates with a water supply pipe 12 so that water is caused to fall 45 in a spray or shower into the cross-tubes 5.

At the top of the structure is shown a pan B supplied with water from a supply pipe 14 and from which an overflow pipe 13 leads to the bottom of the uppermost chamber y, or 50 the pipe 13 may lead directly from the pipe 14. From the top of the uppermost chamber y an overflow pipe leads to the bottom of the next chamber y, and the overflow pipe from the top of the latter leads to the bottom 55 of the chamber y next below, and so on,

the overflow pipe 15 from the lowest chamber y leading to the sewer or other discharge duct.

Where the structure is round in cross section and the chambers y are not subdivided there is but one overflow and one inlet to each, but when, as in the case of a rectangular structure, there is a series of chambers y to each of the four walls there is an overflow and inlet to each, or all those on the same level may have communicating ports or 60 necks with one inlet and one overflow to each series. The bottom of the chamber X has or is formed into a pan or basin Y provided with a discharge pipe 17.

As thus constructed the gases or vapors to be condensed flow into the chamber X from the pipe 8 and coming in contact with the surfaces of the tubes 5 are thereby cooled and condensed and flow off through the discharge pipe 17, and when a spray is used the water thereof will combine with or cool the gases and vapors, and aid in condensing or will combine with or form a solution with the same, and the solution or mixture will 65 collect in the pan Y and be conducted out by the pipe 17.

It will be seen that in each compartment or chamber y the colder water enters at the bottom and as it becomes heated flows upward 70 so that the direction of flow coincides with that resulting from the increase of temperature, although the body of water as a whole passes from the top of the structure downward; that a very extended cooling area is 75 secured in a comparatively limited space; that the water can be circulated over this entire area with great rapidity; and that water or any desired solution can be brought 80 into direct contact with the gas or vapor in a finely divided condition, and aids in condensation and in securing a solution of the matter 85 contained in the gas or vapor.

While the described apparatus is adapted 90 for use as a condenser in many different applications, it is especially serviceable for use in the manufacture of sulfuric acid, where one or more of the structures is arranged to receive the gases from a Glover tower and between the usual chambers. In such case 95 there is a frame-work K consisting of vertical posts and cross beams supporting casings of lead which with an inner lining 1 of lead, inclose the various chambers, the tubes 5 being 100 of lead or lead covered.

Without limiting myself to the construction shown, I claim:

1. A condenser consisting of a series of superposed casings, each with a chamber, 5 series of horizontal tubes 5, on different parallel horizontal planes each series communicating at the ends with different parts of its casing and pipes arranged to direct fluid from the top of one casing to the bottom of 10 the casing below.
2. In a vapor condenser the combination of series of superposed horizontal tubes arranged transversely of a chamber, a casing communicating with each end of each series 15 of tubes, and pipes and connections arranged to direct water downward through the succeeding series of tubes but upward from the lower to the upper tubes of each series.
3. In a vapor condenser the combination 20 of series of superposed horizontal tubes arranged transversely of a chamber, a casing communicating with each end of each series of tubes, pipes and connections arranged to

direct water downward through the succeeding series of tubes but upward from the lower 25 to the upper tubes of each series and means for distributing liquid upon the tubes, and an inlet for gases at the bottom of the chamber.

4. The combination in a condenser, of series of casings enclosing a central chamber, independent series of horizontal tubes connecting opposite casings, pipes connecting the top of one casing with the bottom of the next lower casing, a tank at the top of the 35 structure connecting with the bottoms of the next casing below, a supply pipe leading to said tank, and a spray device above the upper series of tubes.

In testimony whereof I affix my signature 40 in presence of two witnesses.

JOHN CALHOUN CLARK.
